(57) **CLAIM**

What is claimed is the ornamental design for a hospital bed headboard cover with pockets, as shown and described.

DESCRIPTION

FIG. 1 is a perspective view of a hospital bed headboard cover with pockets, illustrated with tie strings tied around legs of a bed, showing the new design;

FIG. 2 is a front elevational view thereof, illustrated with the tie strings untied;

FIG. 3 is a rear elevational view thereof, illustrated with the tie strings untied;

FIG. 4 is a left-side elevational view thereof, illustrated with the tie strings untied, the right-side elevational view being a mirror image thereof;

FIG. 5 is a top plan view thereof, illustrated with the tie strings untied; and,

FIG. 6 is a bottom plan view thereof, illustrated with the tie strings untied.

The broken lines showing a bed in FIG. 1 are included for the purpose of illustrating the invention in use, and form no part of the claimed design.

The broken lines in the figures represent stitching and form a part of the claimed design.
